Anthony Naiden, Southwick, Mass., assignor, by mesne assignments, to The Coca-Cola Company, Wilmington, Del., a corporation of Delaware

Application June 22, 1946, Serial No. 130,942

Term of patent 14 years

(Cl. D52—3)

To all whom it may concern:

Be it known that I, Anthony Naiden, a citizen of the United States, residing at Southwick, in the county of Hampden and State of Massachusetts, have invented a new, original, and ornamental Design for a Beverage Dispenser, of which the following is a specification, reference being had to the accompanying drawing, forming a part thereof.

Fig. 1 is a front perspective view;

Fig. 2 is a front elevation; and

Fig. 3 is a side elevation of a beverage dispenser embodying my new design.

I claim:

The ornamental design for a beverage dispenser, substantially as shown.

ANTHONY NAIDEN.
